UNITED STATES PATENT OFFICE.

CARL P. ASTROM, OF EAST ORANGE, NEW JERSEY, ASSIGNOR TO M. H. TREADWELL COMPANY, A CORPORATION OF NEW YORK.

DUST-GUARD.

1,211,037.

Specification of Letters Patent.

Patented Jan. 2, 1917.

Application filed May 7, 1914. Serial No. 836,840.

To all whom it may concern:

Be it known that I, CARL P. ASTROM, a citizen of the United States, residing at East Orange, in the county of Essex and 5 State of New Jersey, have invented certain new and useful Improvements in Dust-Guards, of which the following is a full, clear, and exact specification.

This invention relates to an improved arrangement of dust guard for journal boxes and the like, the especial object of the invention being the provision of a device of this character which will insure an exceedingly tight closure against the passage of 10 dirt or fire into or out of the journal box and is so constructed that the bearings for the shaft entering the box may be removed and new ones substituted, thus giving the main portion of the guard a permanent 15 character.

Further advantages of the improved dust guard lie in the fact that it may be constructed by stamping it from sheet metal, rendering the guard fireproof, easy and 20 cheap of manufacture, and capable of easy application to the journal box and removal therefrom.

A further object of the invention is the provision of an improved bearing for the 25 guard, constructed in sections and having the sections so joined that they are capable of inward movement to accommodate wearing away of the metal, and at the same time a practically impervious joint is provided 30 preventing the passage of fire, or foreign matter into the journal box at this point.

A full understanding of the invention will be obtained from the following description of a construction embodying the same, 35 taken in connection with the accompanying drawings illustrating its several features in a preferred form and the scope thereof specifically pointed out by the appended claims.

40 In the drawing, Figure 1 is a plan of the improved dust guard; Fig. 2 is a side elevation of the same; Fig. 3 is a section through an axle box of the type employed in railway cars illustrating one mode of 45 applying my invention; Fig. 4 is a view illustrating the parts of the dust guard separated to permit their application to the axle box; Fig. 5 is a detail of the improved bearing for the shaft or axle entering the

box; and Fig. 6 is a fragmentary detail 55 view of the lower portion of the dust guard.

In the form of my invention shown, the dust guard consists of a plurality of co-operating interlocking sliding members 1 and 2 constituting a frame, adapted to receive the shaft. The guard carries removable grooved sections 4 and 5 of Babbitt or other suitable bearing metal. One section 4 is detachably secured to the upper member 1 of the frame, and the other section 5 60 similarly secured to the lower member 2 of the frame, so that when the two members are assembled the two sections unite to form a continuous bearing as shown in Fig. 3. As stated, the two members constituting the 65 frame may be constructed of sheet metal in such a manner that one of the members has an interlocking sliding connection with the other member. This is accomplished in the following manner: The upper member 1 70 comprises a plate having its central portion partially cut away from one end to provide inner side elongations 8 and 9, the inner edges of which merge into the central edge 7 of the substantially semicircular cutaway 75 portion. These elongations are adapted to enter slots or grooves in the lower member 2 of the frame, when the parts are assembled. A filler plate 10 less in width than the plate 1 is secured to said plate in any 80 convenient manner, for instance, by rivets 11, 12. The projecting edge 13 of plate 1 constitutes a tongue adapted to receive a groove in the bearing section 4 to retain it in place. The upper end of the plate 1 has 85 its sides 14 and 15 beveled or sloping, and that portion of the metal at their junction bent at right angles to form a centrally located wing 16 to which is pivotally secured a leaf spring 17, as by rivet 18. The lower 90 member of the frame is similarly constructed of stamped sheet metal plates and consists of parallel plates 19 and 20, separated by plate 29, each plate having its central portion cut away in the same manner as in 95 the upper member 1 to provide side elongations 21 and 22 on the plate 19, and like elongations 23 and 24 on the plate 20. The bearing segment 5 has a groove which fits on plate 29, and plates 19 and 20 are cut out 100 larger in order to receive the edges of the bearing 5. The elongations 23 and 24 extend beyond the elongations 21 and 22 and

105

their ends are bent at right angles forming shoulders 25, 26, under which the curved ends 27 and 28 of the spring 17 rest when the guard is assembled. Leaf springs 33 and 34 having one end secured to one of the external plates, as 19, of one member and their other ends resting against the plate serve to press the guard against the outer wall of the journal box and prevent dust and other foreign matter from entering, or fire from flashing out.

The two members are assembled by bending back the elongations 23 and 24 so as to afford a clearance for the entry of the elongations 8 and 9 on the upper member at the points of the shoulders 24 and 25, and by sliding said elongations on the upper member into the grooves 31, 32 and inserting the ends of the leaf spring 17 under said shoulders 25, 26. It will be observed that pressure in one direction is thereby imparted to the lower member of the frame, and pressure in the opposite direction to the upper member, so that the two members tend to contract on the wheel shaft. This pressure is exerted at all times, and keeps the bearing metal in continuous contact with the axle as the bearing metal wears away. The guard thus automatically accommodates itself to changes in circumference due to wearing away of the metal.

The mode of joining the two bearing sections is such that they may be permitted the desired range of movement above indicated and at the same time form a continuous closure to prevent entry of dirt, dust and other foreign substances into the interior of the box, or the exit of fire or combustible gases from an overheated bearing. Such passage of gases or flame through the inner side of a box has been known to set a car on fire. This is prevented by cutting or notching the inner ungrooved portion of each section to provide notches or lugs 35, 36, and completely cutting away the extreme ends so that a type of stepped scarf joint is formed. When the two sections are assembled the lugs of one member enter notches of the other member, permitting sliding of the sections and at the same time, maintaining a continuous closure around the axle at the inner side of the box. To assist this, the outer side of the guard is made flush, so that it tightly fits against the outer shoulder 47 of the box.

For purposes of illustration, I have shown in Fig. 3 a mode of applying my dust guard to a car axle box of standard type. The axle box consists of a box frame 37 adapted to receive a suitable lubricant and its vehicle, for instance, tow or cotton waste. A hinged cover 38 normally closed by means of a spring 39 permits access to the box from the exterior. The car axle 40 projects into the box through the internal opening 41 and

its journal 42 contacts with a brass 43 held in place by a key 44 in the usual manner. A collar 45 at the end of the axle prevents longitudinal slipping of the brass during rotation. In the rear of the axle box is provided a dust guard well 46 of usual type into which the dust guard is dropped before the axle is projected into the box. The upper section 1 of the dust guard is joined in interlocking relation with said lower section 2 by sliding the elongations 8 and 9 into the grooves 31 and 32 in the lower member and passing the ends of the leaf spring 17 under the shelves 25 and 26 in the lower member. The pressure of springs 33, 34 acts to press the sections of the bearing against the shoulder 47 of the box, and the spring 17 keeps the bearings 4, 5 in constant contact with the axle as the metal wears away. While the axle is being inserted, the parts of the dust guard are held spread apart to permit the axle end to pass through.

It will be noted that I have thus provided a dust guard which is exceedingly simple in construction, easy to manufacture at a very slight cost, and capable of ready and quick application to the journal box or other device with which it is associated.

It will be seen that the present invention provides not only a self-contracting dust guard which performs the ordinary function of excluding dust from entering the bearing, and preventing loss of oil from the bearing, but it is also fire-proof, and prevents escape of hot combustible gases or flames from the bearing itself, or passage of fire into the box.

One contemplated use of this invention is for cinder cars, where there is danger with ordinary boxes of setting the bearings on fire from hot cinder. Railway bearings frequently become overheated and take fire, and these fires have been known to communicate to the car by passing through the inner side of the box, or gases escaping through the inner side of the box have become ignited, as from hot cinder, and set fire to the car or to the bearing. The present construction keeps the fire in the box.

A further advantage of this invention resides in the provision of the U-shaped renewable bearing segments 4 and 5. As these wear away, the pieces will drop, and can easily be removed, which is a distinction over a T-shaped bearing metal segment which would leave the shank of the T in the slot between the plates. In the broad aspect of the invention T-shaped bearing segments are within the scope of this invention, equally with the specific U-shaped form shown. It will also be observed that no rivets or fastenings are employed for the bearing metal segments.

A further advantage of the construction herein described is that the front or outer

side of the dust guard is substantially flush, so that it fits the shoulder 47 of the box, this shoulder being at present a standardized element in M. C. B. or other standard railway 5 boxes.

It is to be understood that my invention is not to be limited to the exact details of construction herein shown, nor to the method of application which is shown merely for 10 purposes of illustration, as the invention is capable of wide variation and considerable modification and may be adapted for other uses as well without departing from the spirit and scope thereof.

15 Having thus described my invention, what I declare as new and desire to secure by Letters Patent of the United States is:—

1. A dust guard comprising a U-shaped member formed by a pair of spaced plates 20 secured together, a coöperating U-shaped member adapted to slide between said spaced plates, bearing segments carried by said members and spring means carried by one member and engaging the other to draw 25 them together.

2. A dust guard comprising a U-shaped member formed by a pair of spaced plates secured together, a coöperating U-shaped plate member sliding between said plates, bearing segments carried by said members and having their faces on one side in the 30 same plane with the side faces of the members.

3. A dust guard comprising a pair of 35 spaced U-shaped plates secured together, one of said plates having inturned ends, a coöperating member sliding between said spaced plates and below said inturned ends, a spring between said member and said 40 ends, and bearing segments carried by said

member and said plates and pressed together by said spring.

4. A dust guard comprising spaced U-shaped plates secured together, a spacing member between said plates, a second member 45 carrying a filler plate and sliding between said plates, a spring between said second member and said spaced plates, and bearing segments grooved to fit said members, said plates and bearing segments having their faces on one side in a common plane.

5. A dust guard comprising a pair of U-shaped plates secured together, a spacing member between them projecting into the 55 space between their arms, a bearing segment grooved to fit the projecting end of said spacing member and engaging the edges of said plates, a second member sliding between said plates and carrying a second bearing 60 segment, said second member and segments having their faces on one side flush with the side face of one of said plates, and a spring acting between said second member and said plates.

6. A dust guard comprising a member having projecting arms to straddle a shaft, shoulders on said arms, a coöperating member slidably engaging said arms, a spring carried by said coöperating member and 70 separably engaging said shoulders for contracting said members on the shaft, and bearing segments carried by said members.

In testimony whereof I affix my signature, in presence of two witnesses.

CARL P. ASTROM.
